UNITED STATES PATENT OFFICE.

CROCKER H. SANFORD, OF BALTIMORE, MARYLAND.

MENTHOL INHALER AND PENCIL.

1,102,086.

Specification of Letters Patent. Patented June 30, 1914.

Application filed September 26, 1913. Serial No. 792,040.

To all whom it may concern:

Be it known that I, CROCKER H. SANFORD, a citizen of the United States, residing at Baltimore, State of Maryland, have invented new and useful Improvements in 5 Menthol Inhalers and Pencils, of which the following is a specification.

This invention relates to a combined menthol inhaler and pencil, the object of the invention being to provide a simple, inexpensive and efficient device of this character including a casing adapted to contain a body of menthol and to permit of the flow therethrough under suction of air which will be 10 impregnated with the menthol vapors for inhalation.

A further object of the invention is to provide a device of the character stated in which the casing embodies novel means for 20 holding a charge of menthol and circulating air therethrough, said casing including a removable cap adapted when detached to expose the body of menthol so that it may be employed as a medicinal pencil.

25 The invention consists of the features of construction, combination and arrangement of parts, herein described and claimed, reference being had to the accompanying drawing in which:—

30 Figure 1 is a central longitudinal section through a combined menthol inhaler and pencil constructed in accordance with my invention. Fig. 2 is a transverse section on the line 2—2 of Fig. 1. Fig. 3 is a transverse 35 section on the line 3—3 of Fig. 1.

In carrying my invention into practice, I provide a casing comprising tubular body and cap sections 1 and 2, the outer end of the cap section being preferably of conoidal 40 or rounded form so that it may be conveniently fitted in the nostrils for inhalation purpose. The inner end of the cap section is adapted to fit over or have a slipjoint connection with the inner end of the body section, which latter is provided with a stop 45 bead or projection against which the cap section is adapted to abut when fully applied.

The device as a whole is in the form of an 50 elongated tubular body of a length and diameter to be conveniently handled, and, if desired, to be carried in the pocket or other suitable receptacle. Fixed within the inner end of the body section 1 is a supporting 55 plate 4 having an out-turned flange 5 bear-

ing against the wall of the body section, a central opening 6, and an annular series of air passages or ports 7 surrounding said opening. A chamber is thus provided at the inner end of the cap to receive a body of 60 menthol 8, which is of a length to project beyond the inner end of the body section and of a diameter to snugly fit therein, and is provided with a tapered longitudinal passage 9.

The cap section 2 when applied is adapted to cover and project the menthol body and prevent the loss of the volatile constituents thereof, and said cap carries an eduction or discharge tube 10 also preferably of slightly 70 tapered form, but which may be of the same diameter throughout. The outer end of this tube opens through and is fixed to the outer end of the cap, while the inner end of the tube is adapted to engage over the outer 75 conical end of a guiding and supporting stud 11 tightly fixed within the opening 6 of the plate 4, whereby the inner end of the tube is closed and the tube firmly supported in position when the cap is applied.

The outer end of the cap forms a collection chamber for air impregnated with the menthol vapors, and the tube 10 serves as a conductor through which these vapors are discharged. The air to be impregnated is 85 drawn into the body section 1 through the annular series of openings 12 therein, which openings are normally covered and closed by the inner end of the applied cap, but by slightly drawing out the cap the said openings may be exposed to allow air to enter. The air entering the body section through the openings 12 passes through the perforations 7 in the plate 4, and thence through the tapered passage 9 in the menthol body 95 8, and thence into the said collection chamber for discharging. It will be observed that the tapered opening in the menthol body exposes the apertures 7 and permits the air from the body section 1 to freely enter the cap, while the air will be slightly retarded in its flow by the contraction of the passage 9 to insure its coming directly in contact with the body of menthol for the extraction of the volatile essences therefrom. The 105 opening in the tube further permits the impregnated air contained in the collection chamber to flow outward through the tube, the inner end of which is normally closed by the stud 11, which serves as a stopper or 110

valve, when, however, the cap is slightly drawn out to expose the openings 12, the inner end of the tube will also be drawn away from the stud or stopper, thus allowing the impregnated vapors to discharge therethrough. By entirely detaching the cap and tube 10, the body of menthol will be exposed so that it may be used as a medicinal pencil in the ordinary way, as will be readily understood, the body section 1 serving in this case as a manipulating handle. It will be apparent that when the cap section is fully applied the escape of vapors will be entirely prevented, thus enabling the enclosed charge of menthol to be preserved for practically indefinite use.

I claim:

1. A device of the character described comprising a body section having air inlets, a cap section detachably mounted upon the body section and adapted to be removed therefrom and adjusted to expose said air inlets, a socket upon the body section having air passages communicating with said body section, a body of menthol fitted within and projecting from the socket and provided with a tapering passage communicating with said air passages, a stopper carried by the body section and projecting into said socket and passage in the menthol body, and a tube carried by the cap and projecting into the passage in the menthol body and adapted to

be closed by said stopper when the cap is fully applied.

2. A device of the character described comprising a tubular body section having air inlets, a supporting plate carried by said body section between said air inlets and the inner end thereof, said supporting plate having air passages, a body of menthol resting upon the said supporting plate and partially inclosed by the inner end of said body section, said body of menthol having a passage communicating with said air passages, a stopper upon the plate projecting into said air passage in the menthol body, a cap section detachably mounted upon the body section and adapted to normally inclose the menthol body and cover the inlets and to be adjusted to a prescribed position to expose said inlets, and a discharge tube on the cap section adapted to project into the passage in the menthol body and to be closed by said stopper when the cap section covers the air inlets and to be moved away from said stopper when said cap section is adjusted to expose the air inlets.

In testimony whereof I, affix my signature in presence of two witnesses.

CROCKER H. SANFORD.
